United States Patent Office

Des. 210,866

Patented Apr. 30, 1968

210,866

BOTTLE

Wilfred V. Wickham, 1448 Adelaide St., London,
Ontario, Canada

Filed Mar. 6, 1967, Ser. No. 6,063

Term of patent 7 years

(Cl. D9—32)

FIG. 1

The dominant features of my design reside in the portion shown in full lines.

I claim:

The ornamental design for a bottle, as shown and described.
